UNITED STATES PATENT OFFICE

2,196,886

VOLTAGE REGULATION

Elliot Q. Adams, Cleveland Heights, Ohio, assignor to General Electric Company, a corporation of New York

Application July 17, 1937, Serial No. 154,294

11 Claims. (Cl. 171—119)

My invention relates generally to voltage regulation and more particularly to the compensation of load circuits for variations in voltage drop caused by variation in current in their supply circuits.

Much trouble is experienced with flickering of incandescent lamps caused by instantaneous variations in voltage caused by starting motors, arc welders, and other fluctuating power loads drawn from the same feeder lines. These variations are so large, in many cases, that no practicable increase in the wire sizes will reduce the variations to an acceptable range.

I have found that by drawing the lighting and power loads, respectively, from the two sides of a 3-wire load circuit, and adjusting the impedance of the common neutral to a proper relation to the impedance of the common supply side of the circuit, that the flickering of the lamps caused by variations in the power load can be eliminated; and this adjustment remains good for all reasonable values of the lighting and power loads.

This result is explainable as follows: In a three-wire circuit, current in the two sides of the circuit flows in opposite directions in the common neutral. Therefore, if the load current of one side causes a voltage drop in the common neutral with respect to that side, the same current will produce a voltage rise with respect to the other side. This voltage rise I utilize to cancel the voltage drop caused by the current producing it in the supply side of the circuit.

While my invention is particularly adapted for use with the three-wire transformer secondaries of conventional single phase distribution transformers it may also be used in three-wire direct current circuits and in polyphase alternating current circuits.

An object of my invention is to improve the voltage regulation of load circuits.

Another object of my invention is to prevent lamp flicker as the result of fluctuating loads applied to a main supply circuit which also supplies current for incandescent lamps.

A further object of my invention is to improve the voltage regulation of one side of a three-wire transformer secondary by properly relating the impedance of the common neutral to the impedance of the primary circuit of the transformer.

My invention will be better understood from the following description, taken in connection with the accompanying drawings, and its scope will be pointed out in the appended claims.

In the drawings, Fig. 1 illustrates diagram-

matically an embodiment of my invention using a single phase insulating transformer; Fig. 2 is a modification using a single phase auto-transformer; and Figs. 3, 4 and 5 are modifications using three-phase transformers.

Referring now to Fig. 1 of the drawings, a transformer, having a primary winding 10, has secondary winding sections 11 and 12 connected respectively between a common neutral conductor 13 and the outer sides of a three-wire load circuit. To the side of this circuit supplied by secondary section 11 is connected a load, the voltage of which it is desired to make independent of the load on the other side. This load is shown by way of example as a lamp load 14, the connections of which are controlled by switches 15. To the side of the three-wire circuit supplied by secondary section 12 is connected a variable power load, shown by way of example as a pair of induction motors 16, the connections of which are controlled by switches 17. The circuit of primary winding 10 is energized by any suitable source of alternating current (not shown).

Of the letters on the drawings, V denotes voltage; I—current; Z—impedance and n—number of turns. The subscripts denote respectively: 0—circuit of primary 10; 1—secondary section 11; 2—secondary section 12; and 3—common neutral.

It can be shown, by calculation, that neglecting magnetizing current, stray flux, and such part of the iron losses as cannot be assigned to one of the circuits, the voltages available for the two secondary loads are respectively:

$$V_1 = \frac{n_1}{n_0} V_0 - I_1 \left[\left(\frac{n_1}{n_0} \right)^2 Z_0 + Z_1 + Z_3 \right] - I_2 \left[\frac{n_1 n_2}{n_0^2} Z_0 - Z_3 \right] \quad 35$$

$$V_2 = \frac{n_2}{n_0} V_0 - I_2 \left[\left(\frac{n_2}{n_0} \right)^2 Z_0 + Z_2 + Z_3 \right] - I_1 \left[\frac{n_1 n_2}{n_0^2} Z_0 - Z_3 \right] \quad 40$$

The last term of each equation represents the change in voltage of one side of the transformer secondary caused by the load on the other side.

By making Z_3 equal to

$$\frac{n_1 n_2}{n_0^2} Z_0 \quad 45$$

the last terms vanish, and the voltage of each side of the transformer secondary becomes independent of variations in the current taken by the other side. The term

$$\frac{n_1 n_2}{n_0^2} Z_0$$

may be referred to as the equivalent primary circuit impedance referred to the secondary.

The impedances Z_0 , Z_1 , Z_2 and Z_3 are distributed throughout their respective circuits. Z_3 , however, in order to have the proper value and power factor or angle

5

$$\left(\tan^{-1} \frac{X}{R} \right)$$

may contain added lumped impedance elements. These elements may be reactive or resistive or 10 both. If reactive they may be positive (inductive) or negative (capacitive). If resistive they may also be either positive (ordinary resistor) or negative (series connected commutator type generator or self-excited induction generator). 15 Z_3 should ordinarily have the same power factor or impedance angle as Z_0 .

It is also important that there be a point at which the common neutral impedance Z_3 terminates. In Fig. 1 this is the point on neutral 20 conductor 13 at which the two load circuits branch off and become entirely separate. Usual wiring practice will make the common neutral terminate at the panel board.

Instead of matching Z_3 to Z_0 , Z_0 may be matched 25 to Z_3 by making

$$Z_0 = \frac{n_0^2}{n_1 n_2} Z_3$$

In case an auto-transformer is used, the equations 30 are more complicated, but nevertheless there is a value of the impedance in the common neutral for which the voltage in each side of the secondary of the transformer is independent of the current on the other side.

Taking a rather general case of an auto-transformer as illustrated in Fig. 2, the letters and 35 subscripts are the same as for Fig. 1 except that 4 and 5 denote the windings between the respective primary taps and the common neutral of the secondary.

$$V_1 = \frac{n_1 + n_4}{n_4 + n_5} V_0 - I_1 \left[\left(\frac{n_1 + n_4}{n_4 + n_5} \right)^2 Z_0 + \left(\frac{n_1 - n_5}{n_4 + n_5} \right)^2 Z_4 + \left(\frac{n_1 + n_4}{n_4 + n_5} \right)^2 Z_5 + Z_1 + Z_2 \right] - I_2 \left[\frac{(n_1 + n_4)(n_2 + n_5)}{(n_4 + n_5)^2} Z_0 + \frac{(n_2 + n_5)(n_1 - n_4)}{(n_4 + n_5)^2} Z_4 + \frac{(n_1 + n_4)(n_2 - n_4)}{(n_4 + n_5)^2} Z_5 - Z_3 \right]$$

$$V_2 = \frac{n_2 + n_5}{n_4 + n_5} V_0 - I_2 \left[\left(\frac{n_2 + n_5}{n_4 + n_5} \right)^2 Z_0 + \left(\frac{n_2 - n_4}{n_4 + n_5} \right)^2 Z_5 + \left(\frac{n_2 + n_5}{n_4 + n_5} \right)^2 Z_4 + Z_2 + Z_3 \right] - I_1 \left[\frac{(n_2 + n_5)(n_1 + n_4)}{(n_4 + n_5)^2} Z_0 + \frac{(n_1 + n_4)(n_2 - n_4)}{(n_4 + n_5)^2} Z_5 + \frac{(n_2 + n_5)(n_1 - n_4)}{(n_4 + n_5)^2} Z_4 - Z_3 \right]$$

Various special cases can be derived from this by omitting (i. e., placing equal to zero) certain of the n 's and Z 's, e. g.: $Z_4 = Z_5 = 0$ gives the analytic equivalent of an insulating transformer. 60 $n_1 = n_2 = 0$ gives the symmetrical two-coil auto-transformer case. $n_2 = n_4 = 0$, $Z_4 = 0$ gives the unsymmetrical two-coil auto-transformer case. This last arrangement is particularly useful where 65 one of the circuits requires a very small part of the total power, since it permits the use of a correspondingly small transformer.

In the last factor in square brackets, the terms in Z_4 and Z_5 may in the general case, and in the symmetrical two-coil auto-transformer case 70 will, have a resistance component negative in sign. These negative components should not be so large as to overbalance the resistance component of the term in Z_0 , or no static impedance Z_3 can be used to make the last factor in square brackets vanish. Stated otherwise, the resist- 75

ances of the coils n_4 and n_5 should not be too large. It is unlikely, however, that this condition will call for wire in coils n_4 and n_5 any larger than is required by good transformer practice.

No such difficulty arises in the case of an un- 5 symmetrical two-coil auto-transformer.

The power consumed in an impedance in the common neutral is, of course, zero at no load, and likewise zero if the current in the neutral is zero, that is, when the currents taken by the 10 two sides of the secondary are equal. In a balanced system this will be the case when the system is fully loaded, hence the maximum voltage drop under load will not be increased by the presence of the impedance in the neutral. It 15 will, however, occur when the particular line is fully loaded, even if other lines are lightly loaded.

In Fig. 3 the invention is extended to a poly-phase case. Motor 16 is connected as a conventional three-phase induction motor to the 20 terminals of the delta secondary winding of a three-phase transformer. The phase windings of the secondary are extended and lamp loads 14 are connected between the terminals of the extensions and the motor leads which then act as 25 common neutrals. Most three-phase voltages are 220 and if the secondary extensions are also 220 volts, balancing transformers 18 can be used to obtain 110 volts for the lamps.

To obtain proper regulation in Fig. 3, the im- 30 pedance angle of Z_3 should be 30° different from that of Z_0 because unity power factor motor current flowing through Z_0 will be 30° out of phase with unity power factor lighting current flowing through Z_3 .

The circuit of Fig. 3 does not permit ground- 35 ing of one side of each of the lamp circuits.

Fig. 4, however, shows a three-phase circuit in which the neutral impedances Z_3 have the same phase angle as the primary or supply circuit impedance and in which a side of each of the lighting circuits may be grounded so as to conform to usual house wiring practice. 40

As shown in Fig. 4, the individual phase windings of a three-phase transformer winding are 45 star-connected by means of three neutral impedances Z_3 connected respectively between a neutral point, shown grounded, and corresponding intermediate points on each of the phase windings. This polyphase winding may either 50 be the secondary winding of an insulating transformer excited by any suitable primary winding, or it may be considered an auto-transformer energized by any suitable supply circuit.

Three of the winding sections whose potentials 55 are 120 electrical degrees apart are connected to supply any suitable balanced three-phase load, such for example as the motor 16 in Fig. 3. The remaining three winding sections are connected to ground through separate lamp loads 14. 60

As similar power factor three-phase and lighting load currents are in line (phase opposition) in the neutral impedances Z_3 these impedances will have the same phase angle as that of Z_0 , so that merely by relating Z_3 and Z_0 65 as explained above in connection with Figs. 1 and 2, the lamp voltages will be independent of three-phase load fluctuations.

In Fig. 5, the individual phase windings are 70 mesh-connected through the neutral impedances Z_3 which interconnect respectively, the intermediate or neutral points on each of the windings with the outer or free ends of the power circuit sections of these windings.

The three-phase load is connected to the outer

ends of the power circuit sections of the three windings, and lighting loads are connected between the outer ends of the lighting load sections of the windings and the three-phase load connection points.

As the neutral impedances Z_3 carry the three-phase load currents instead of the three-phase load line currents, which are 30° out of phase with each other, the load and lighting currents in the neutral impedances Z_3 will be in line at the same power factor and Z_3 will have the same angle as Z_0 . Z_3 and Z_0 will, of course, be related to each other in accordance with the formulas developed above in connection with Figs. 1 and 2.

15 The number of turns of the power and lighting sections of each three-wire transformer secondary may of course be any values desired and need not be equal as indicated in the first four figures.

20 While I have shown and described particular embodiments of my invention it will be obvious to those skilled in the art that changes and modifications can be made, and I therefore aim in the appended claims to cover all such changes 25 and modifications as fall within the true spirit and scope of my invention.

What I claim as new and desire to secure by Letters Patent of the United States, is:

1. In combination, a transformer, a primary winding circuit therefor, and a three-conductor secondary winding circuit therefor, said secondary winding circuit including a common neutral conductor, said primary winding circuit having an impedance which causes a voltage change on 35 one side of said secondary winding circuit when a load is placed on the other side of said secondary winding circuit, said common neutral conductor having an impedance which produces an opposite direction change in voltage on said 40 one side of said secondary winding circuit when said load is placed on the said other side of said secondary winding circuit, said voltage changes being substantially equal in magnitude.

2. In combination, an alternating current 45 supply circuit, a transformer having its primary winding connected thereto, and a pair of loads connected to the secondary winding of said transformer in such a manner that the power components of the two load currents flow in opposite 50 instantaneous directions in a common neutral conductor, the impedance of said common neutral conductor being substantially equal to the equivalent primary circuit impedance with respect to the secondary current taken by at least 55 one of said loads.

3. In combination, a power supply circuit, a transformer having a primary winding of no turns connected to said supply circuit, a pair 60 of loads connected respectively between an intermediate point on the secondary winding of said transformer and two points thereon on opposite sides of said intermediate point, said two points being spaced n_1 and n_2 turns respectively from said intermediate point and an impedance Z_3 65 connected between said intermediate point and said loads, the value of said impedance being so correlated to the impedance Z_0 of the primary winding circuit of said transformer that Z_3 is substantially equal to

70

$$\frac{n_1 \cdot n_2 Z_0}{(n_0)^2}$$

4. In combination, a transformer having a 75 three-wire secondary circuit provided with a

common neutral, a power load connected to one side of said circuit and a lighting load connected to the other side of said circuit, the impedance of the common neutral being substantially equal to the equivalent primary circuit impedance of said 5 transformer referred to said secondary circuit.

5. In combination, an electric circuit having a supply side and a three-wire load side, said supply side having a given impedance, separate loads connected to each half of said three-wire load side through a predetermined neutral impedance, said supply side impedance being such as to produce a substantial change in the voltage of one of said loads in response to a given change in value of the other of said loads, said neutral impedance being such as to produce a substantial change in the voltage of said one load in response to said given change of said other load, said voltage changes being substantially equal 15 and opposite.

6. In combination, a polyphase load circuit, a plurality of single phase transformer windings interconnected to form a polyphase transformer secondary winding for energizing said load circuit, a plurality of impedances connected to be 25 traversed by the phase currents in said load circuit, extensions on each of said single phase windings, single phase loads connected to be individually energized by said extensions through 30 said impedances respectively, a polyphase primary exciting circuit for said windings having a given impedance, each of said plurality of impedances being substantially equal to the equivalent primary circuit impedance referred to its 35 respective secondary winding circuit.

7. In combination, a plurality of single phase three-wire transformer secondary windings, a polyphase load circuit energized by all of said windings, separate single phase loads energized 40 by each of said windings, the neutrals of each of said windings having an impedance which is common to one of the phases of said polyphase circuit and one of said single phase loads, and an exciting circuit for said windings having a given impedance, each of said neutral impedances 45 being substantially equal to the equivalent exciting circuit impedance referred to its respective secondary winding.

8. In combination, a transformer having a 50 polyphase primary winding and a mesh-connected secondary winding, a polyphase supply circuit for said primary winding, a polyphase load circuit connected to said secondary winding, extensions on each of the phase windings of said mesh-connected secondary, single phase load circuits connected to be energized by said extensions, 55 separate impedances which are common respectively to one of the conductors of said polyphase load circuit and to one of said single phase load 60 circuits, each of said plurality of impedances being substantially equal to the equivalent primary circuit impedance referred to its respective secondary winding circuit.

9. In combination, a polyphase transformer 65 secondary comprising a plurality of windings, a plurality of impedances connected respectively between said windings and a neutral point, a polyphase load circuit connected to said windings, extensions on said windings on the opposite sides 70 thereof to which said impedances are connected, and single phase loads connected respectively between terminals on said extensions and said neutral point, each of said plurality of impedances being substantially equal to the equivalent 75

primary circuit impedance referred to its respective secondary winding circuit.

10. In combination, a plurality of three-wire transformer secondary windings each having a variable load section and a second load section, a plurality of impedances connected respectively between the neutral of one winding and the outer end of the variable load section of another winding whereby a mesh connection of alternate impedances and variable load sections is formed, a polyphase load circuit connected to the outer ends of said variable load sections, and single phase load circuits connected across said second load sections and the impedances directly connected thereto, each of said plurality of impedances being substantially equal to the equivalent primary circuit impedance referred to its respective secondary winding circuit.
11. In combination, an autotransformer winding, a two-wire supply circuit and a three-wire load circuit therefor, one of the load circuit wires being a common neutral for the other two,

said common neutral being connected to an intermediate point on said winding and having an impedance Z_3 , said supply circuit having an impedance Z_0 and having its two conductors connected to said winding at points which are separated from said neutral by n_4 and n_5 turns of said winding respectively, said n_4 and n_5 turns having respective impedances Z_4 and Z_5 , the other two load circuit wires being connected to said winding at points which are separated from the points to which said supply circuit is connected by n_1 and n_2 turns respectively, the arrangement being such that the total turns between the neutral and the other two load circuit wires are (n_1+n_4) and (n_2+n_5) respectively, said 15 neutral impedance Z_3 being equal to

$$\frac{(n_2+n_5)(n_1+n_4)}{(n_4+n_5)^2} Z_0 + \frac{(n_2+n_5)(n_1-n_5)}{(n_4+n_5)^2} Z_4 +$$

$$\frac{(n_1+n_4)(n_2-n_4)}{(n_4+n_5)} Z_5$$

ELLIOT Q. ADAMS.
